UNITED STATES PATENT OFFICE.

ALEXANDER M. GOW, OF DULUTH, MINNESOTA.

ORE-WASHER.

1,392,413.

Specification of Letters Patent.

Patented Oct. 4, 1921.

Application filed July 16, 1920. Serial No. 396,781.

To all whom it may concern:

Be it known that I, ALEXANDER M. Gow, a citizen of the United States, residing at Duluth, in the county of St. Louis and State 5 of Minnesota, have invented certain new and useful Improvements in Ore-Washers, of which the following is a specification.

This invention relates to ore washers, and particularly to magnetic ore washers.

10 One object of this invention is to efficiently separate magnetic from non-magnetic particles, or separate matter of different degrees of permeability in a simple and practical manner.

15 Another object is to provide a magnetic ore washer simple and durable in construction, in which the parts are arranged to co-operate in a manner to meet all of the requirements for successfully concentrating 20 magnetic ores.

These and other objects are accomplished by means of the arrangement disclosed on the accompanying sheet of drawings, in which—

25 Figure 1 is a vertical longitudinal sectional view of my magnetic ore washer; and, Fig. 2 is a transverse sectional view of the same.

The various novel features of my invention will be apparent from the following description and drawings and will be particularly pointed out in the appended claims.

Referring to the figures of the drawings, it will be noted that my magnetic ore washer 30 preferably includes a vertically arranged tank or shell 10, to the outer side of which is secured a plurality of magnets 11 for the purpose of drawing to the inner wall of the tank magnetic particles which are included

40 in ore supplied to the tank through any suitable supply means, such as a chute 12. Secured to the lower end of the main tank 10

is a settling tank 13 provided with the usual spigot or discharge gate 14, said settling

45 tank preferably being supplied with clean water through branch pipes 15 connecting with a supply pipe 16. Rotatably mounted within the shell or tank 10 is a hollow shaft 17 mounted in any suitable bearing 18 at

50 its lower end and rotated by any suitable mechanism, which may include a gear 19 mounted upon one end of the hollow shaft 17. Secured to the shaft are a plurality of paddles which radiate from the shaft and

55 terminate in relatively straight edges, which preferably are in parallelism with the inner

surface of the tank, and when moved by a rotary action of the shaft just clear the inner surface of said tank for the purpose of scraping from the inner surface of the tank any 60 magnetic material which has been drawn thereto by the action of the magnets 11. The magnetic ore particles are relatively heavy, as compared with the sand or other gangue within the tank, and accordingly 65 when scraped or otherwise removed from the inner wall of the tank 11 by the paddles 20 tend to settle toward the bottom of the tank and pass into the settling chamber 13, this action being augmented by the paddles 70 20 having an angle which tends to thrust the magnetic ore particles downwardly. The sand or other non-magnetic material from which the magnetic material is separated being lighter in weight is caused to 75 move upwardly by rising currents of water, which not only issue through the pipes 15, but also through openings 21 in the hollow shaft 17, it being understood that the main supply of water is forced through said hollow shaft from any suitable water supply 80 pipe 22. The non-magnetic material or gangue caused to rise by the upward currents of water, is discharged from the upper end of the tank through any suitable overflow or 85 spout 23. Preferably the ore supply is located at a point intermediate the concentrate settling tank 13 and the gangue discharge spout 23. By means of this arrangement the ore washer is adapted to separate 90 magnetic from non-magnetic particles of different degrees of permeability in a simple and efficient manner, and also in a manner to meet commercial requirements.

It is my intention to cover all modifications of the invention falling within the spirit and scope of the following claims.

I claim:

1. In an ore washer for separating magnetic from non-magnetic particles or particles of different degrees of permeability, the combination of a vertically arranged tank, means for drawing to the inner surface of the tank magnetic particles of ore deposited in said tank, a vertically arranged 100 rotatable shaft within said tank carrying means for removing the magnetic particles from the inner side of the tank and for causing the same to descend, and means for supplying water to the tank whereby the 105 gangue is caused to flow upwardly and discharge from said tank.

2. In an ore washer for separating magnetic from non-magnetic particles or particles of different degrees of permeability, the combination of a vertical tank for receiving magnetic ore to be washed, means for drawing magnetic particles to the inner side of the tank, and a hollow shaft within said tank carrying paddles for removing the magnetic particles from the inner wall of the tank and causing same to descend, said hollow shaft being provided with apertures whereby water supplied to said hollow shaft passes through said apertures into the tank for causing the gangue to rise and to be discharged from said tank.
3. In an ore washer for separating magnetic from non-magnetic particles or particles of different degrees of permeability, the combination of a vertically arranged tank into which magnetic ore to be washed is deposited, means for drawing magnetic particles of the ore to the inner wall of the tank, a hollow shaft mounted in said tank carrying paddles for removing the magnetic particles from the inner walls of the tank and causing same to descend, and a settling tank at the lower end of said main tank into which the magnetic particles settle, said shaft having openings through which water supplied to the shaft may be discharged into the tank to create rising currents of water for discharging the gangue.
4. In an ore washer for separating magnetic from non-magnetic particles or particles of different degrees of permeability, the combination of a vertical arranged tank into which magnetic ore to be washed is deposited, means for drawing magnetic particles of said ore to the inner wall of the tank, a hollow shaft mounted in said tank carrying paddles for removing the magnetic particles from the inner walls of the tank and causing same to descend, a settling tank at the lower end of said main tank into which the magnetic particles settle, said shaft having openings through which water supplied to the shaft may be discharged into the tank to create rising currents of water for discharging the gangue, means for withdrawing material deposited in said settling tank, and means for supplying additional water to said settling tank.

Signed at Duluth, Minnesota, this 7th day of July, 1920.

ALEXANDER M. GOW.
